HYDRAULIC TIE REMOVER

Harry B. Hughes, Portland, Oreg.

Application May 14, 1943, Serial No. 486,971

5 Claims.

(Cl. 254—43)

This invention relates to a hydraulic tie removing machine of the class disclosed in my subsisting Patent No. 2,283,929 and its principal object is to make more certain the operation of the hydraulic ram in removing ties from beneath a railway track, preparatory to replacement with new ties.

Another object of the invention is to provide a turret revoluble in a horizontal arc, with a hydraulic ram mounted on the turret by trunnions or the like, so that within limits the movement is "universal," as is said of a universal joint, the utility of which will be hereinafter pointed out.

Since a machine of the character referred to must exert pressures often in excess of ten tons, it is an object to construct a machine wherein the reaction to such load is sustained by the turret and turret mounting and from them transferred to the two tracks without tendency to stress and twist the necessary framework required to support the pump, gasoline engine and other auxiliaries incident to a machine of such high load capacity, which will also perform the task of pushing out a tie in a reasonable time, fifty per hour being considered good.

It is a further object to construct a hydraulic ram tie remover and provide it with an adequate tie engaging shoe capable of readily taking hold of a wood tie and sustaining the heavy pressure necessary to push the tie out through the ballast and side earth without digging a trench for it.

Since work of the character indicated must be performed by power machinery, the machinery must have a frame capable of being sustained on a pair of railway tracks and movable thereon from tie to tie requiring replacement, it is at once seen that the frame cannot carry the working load. That is to say that a frame capable of carrying a machinery set-up and capable of exerting a force of well above ten tons, would be badly twisted whenever the work was being done, or otherwise too heavy and therefore expensive to use. It is an object therefore to make a machine wherein the stress reactions developed by pushing out a tie through well set ballast (where it has laid for enough years to require replacement) shall be sustained by the tracks in proportion to their ability to resist the stress, which is unequal as will be hereinafter explained. It is an important object to provide for this.

Drawings on three sheets accompany and form a part of this specification in which,

Fig. 1 is a plan view of a machine which satisfies all of the objects named;

Fig. 2 is a section taken on 2—2, Fig. 1, show-

ing an elevation view of the hydraulic ram that develops the thrust necessary to push out a tie from beneath a pair of tracks of a railway;

Fig. 3 is a front elevation of the machine shown in plan in Fig. 1; and

Figs. 4, 5 and 6 are separated parts, shown isometrically, which, when assembled and bolted together, constitute the principal part of my invention for making the tracks support the thrust load in proper proportion, without putting a wind in the frame upon which the turret, turret base and the operating mechanism are mounted.

In the drawings, letter R is a reversible hydraulic ram. In this case it is a cylinder containing a piston, not shown, which operates a heavy piston rod 2, to drive the tie shoe 3, the teeth 4 of which engage with the tie T to push it out.

Replaceable tie engaging teeth 4 are so formed that their points tend to penetrate the tie T when forced to the right, considering that view of the structure shown in Fig. 2. The words "hydraulic ram" are intended to include all types of instrumentalities commonly called by that name where they are adapted to exert linear force under influence of hydraulic power.

An important feature of the tie shoe 3 is the fact that that part of it which serves to be made rigid with the piston rod 2, is straight along its underside while that portion containing the teeth 4 is arcuate in outline so that as the shoe is forced further from its initial point of engagement with tie T and the tie with it, the rows of teeth 4 successively engage its wood. The head 3a serves to push the tie clear under the rail such as 16 after the teeth 4 will no longer engage it.

The ram R is furnished with a saddle 5, the opposite sides of which are formed as trunnions 6, which are turnably mounted in bearings in the turret 8.

The turret 8 is preferably made in two parts as shown isometrically in Figs. 4 and 5 and both numbered 8 as they are duplicates and bolt together to form a complete turret as shown in Fig. 2. The lower part of both halves of the turret are furnished with a circular pocket of rectangular section, 9, as shown in Fig. 5. These pockets fit turnably into contact with the button 10 of the turret mounting 11, shown in Fig. 6.

Made integral with the turret mounting 11 are a pair of spaced rail hooks 12, so fashioned that when the base 11 is mounted on a part of the frame of the machine as a whole, here shown as a steel channel 13, and the machine is let

down on top of a rail such as 14, the ram being considered to be operating and having pushed the tie T a short distance towards removing it, the reaction generated by the power of the ram and transmitted to the turret and its mounting in part, that part of the reaction stress is applied to the ball of the rail 14 by the hooks 12 with only part of one of the flanges of the channel 13 sustaining any load, and that load in compression.

When a tie is pushed out from under a pair of rails, through the ballast, it tries to climb to the surface with great force, thus putting an outward strain on the other rail of the pair indicated in Fig. 2 by the numeral 16, and unless counter-force is applied will quite often distort the track-age by disturbing the gage. This is overcome by placing a pair of hooks 17 (also shown in Fig. 1) under the rail to engage the lower flange thereof, attaching a bridle chain 18 to the hooks 17 and attaching the bight of the bridle chain to the insulated coupling 19.

From the insulated coupling 19, a single chain 20, also secured firmly to the insulated coupling 19 is held at selective length by the chain grab 21, which is coupled to the top of the turret 8 by the links 22, these instrumentalities being shown in Figs. 1 and 2.

It is to be particularly noted that when so coupled up to the chain and hooks, the turret 8 acts as a lever and the fulcrum is the trunnions 6. The long end of the lever bears against the rail 14, and the short end of the lever, by virtue of the pivot connection 23 for the links 22, transmits more than half of the reaction load of the ram R to the rail 16, thus counteracting the greater thrust load placed on it and serving to equalize the load on both rails.

The ram R, by its piston rod 2, is insulated electrically from the tie shoe 3 by fiber bushings, as shown at 24. This is for the purpose of making the machine available for work on tracks equipped with block signal devices, which the insulated coupling 19 also serves to do.

The rest of the structure drawn is more or less conventional except the hydraulic lift for the machine, when it is to be moved along the track from tie to tie to be removed. The hydraulic lift will be given a general description and its details are not shown completely since it serves as the basis for another application.

The channel 13 (Fig. 2) serves as the main frame member for the machine. To it are attached a hydraulic pump 30 driven by the high speed gasoline motor 31 by means of the shaft 32, the flexible coupling 33, the sprocket 34, silent chain 35 which takes power from the motor at 36. The pump takes fluid from the tank 40 through the tube 41 and delivers it to the control throttle 42 from whence, by manipulating the manual throttle lever 43, fluid under pressure can be directed to either end of the cylinder 1 through hydraulic hoses. While one end of the cylinder is taking fluid from the throttle 42, fluid previously placed in the opposite end of the cylinder 1 reverses its flow through the hose attached to that end and returns to the tank 40 through the tube connection 45. The throttle 42 receives high pressure hydraulic fluid through tubular connection 46 which is connected to the high pressure side of the pump, opposite the inlet 41, as is always the case with pumps of the gear pump variety as shown. Also connected to connection 46 is the tube 48, independently controlled by the valve 49 which serves to furnish power to the hydraulic lift 50.

The machine, as stated, rests on a railway track, directly, while engaged in pushing out a tie. To move to the next position, the wheels 60 and 61 are forced down, raising the machine from the track with respect to its main bulk. A wheel 62 remains in contact with the opposite rail while the machine is working, being supported on a long tubular axle 63. The machine thus runs on three wheels, being slightly overbalanced towards wheel 62 by weight distribution. The axle 63 is insulated by a fiber bushing 64 in the clamp 65.

Wheels 60 and 61 may be raised manually by inserting a crowbar or like instrument in hole 70, thus swinging the bell crank 71 and afterwards raising the other end in the same manner. Preferably, however, the hydraulic lift is used, of which 90 is a double end operating hydraulic cylinder containing opposed pistons, not shown, in abutting connection with piston rods 91 and 92, which operate connecting rods 93 and 94, to operate the bell-cranks 71 and 72 at opposite ends of the machine. An automatically engageable, manually disengageable latch is present but not shown as it would hide more important parts and the hydraulic lift is not herein claimed as inventive.

Having fully described my machine, explained the principle thereof and pointed out the advantages of the parts made subject matter of the claims, what I claim as new and desire to secure by Letters Patent, is:

1. A power operated hydraulic tie remover comprising a hydraulic ram, a toothed tie shoe made rigid with the operating end of said ram, a universal turret in which said ram is mounted, a turret mounting for the turret, a pair of spaced track hooks made integral with said mounting to engage with one of a pair of tracks in such manner that it engages directly with the track, and a frame member for the machine attached to the mounting so that reaction from operating the ram is absorbed directly by the track hooks and not transmitted to the frame.

2. In a hydraulic tie remover, a hydraulic ram, a toothed tie shoe made rigid with the operating end of the ram, a universal turret mounting for the ram including trunnion mountings for the ram in the turret, a chain grab swivelly mounted above the ram on the turret, a bridle chain engageable with the chain grab, track hooks connected to the bridle chain to engage one rail of a railway track, other track hooks beneath the turret mounting positioned to engage the other rail and wherein the reaction force of the ram acting against the trunnions as a fulcrum is unequally applied to the chain bridle with its hooks and the hooks beneath the turret mounting, being greatest against the chain.

3. In a hydraulic tie removing machine, a hydraulic ram, a tie engaging shoe rigidly attached to the operating end of said ram, said shoe being substantially rectangular in plan, that part of its under surface which is nearest to the operating end of the ram being straight, the other part being convexly curved and containing a plurality of spaced, pointed tie engaging teeth that project outwardly and downwardly from said convex surface.

4. A hydraulic tie removing machine comprising a frame, members attached thereto adapting the frame to rest on both rails of a railway track, a motor mounted on the frame, a pump driven by the motor mounted on the frame, a control means for the pump delivery, a hydraulic

ram operable by the pump through said control means, a tie removing shoe operable by the ram against ties by engaging them between the rails of the track to push them in one direction outwardly from beneath the rails, a universal turret mounting upon which said ram is mounted, a mounting therefor that includes a pair of spaced track hooks engageable with the inside of one rail, a plurality of track hooks engageable with the outside of the other rail of the track and a tension chain bridle, one end of which is attached to the upper part of the turret at a point closer to the center of the ram than is the first named pair of track hooks included with the ram mounting, the other end 10 attached to the last named track hooks.

5. A hydraulic tie removing machine having in combination therewith a hydraulic ram, tie engaging means made rigid with the ram and effective upon operation thereof to move a tie with which it is engaged, a universal turret within which said ram is mounted, a turret mounting, spaced track engaging hooks made rigid with said mounting effective to transmit reaction from the ram to the inside of one rail of a pair of railway tracks, spaced hooks engageable with the outside of the opposite rail of said railway tracks and tension members connecting the last named hooks to the turret at a point above the center of the ram.
